TOILET BOWL CLEANER DISPENSER

C. Richard Paulsen, Cincinnati, Ohio, assignor to The Drackett Company, Cincinnati, Ohio

Filed Feb. 5, 1973, Ser. No. 329,464

Term of patent 14 years

Int. Cl. D23—99

U.S. Cl. D23—3

FIG. 1 is a top perspective view of a toilet bowl cleaner dispenser embodying my new design;

FIG. 2 is a side elevational view partially in section;

FIG. 3 is a top plan view thereof; and

FIG. 4 is a bottom plan view thereof.

I claim:

The ornamental design for a toilet bowl cleaner dispenser, as shown.
